UNITED STATES PATENT OFFICE.

FRANK PRETSCH, OF PHILADELPHIA, PENNSYLVANIA.

TOOL HOLDER.

1,413,490.

Specification of Letters Patent. Patented Apr. 18, 1922.

Application filed April 1, 1920. Serial No. 370,506.

To all whom it may concern:

Be it known that I, FRANK PRETSCH, a citizen of the United States, residing at Philadelphia, in the county of Philadelphia and State of Pennsylvania, have invented 5 new and useful Improvements in Tool Holders, of which the following is a specification.

My invention relates to a new and useful 10 improvement in tool holders, and has for its object to so construct such a holder that a series of retaining blocks may be combined therewith in such manner as to firmly hold and guide the tool and obviate the necessity 15 of slotting the body of the tool holder for the reception of the tool.

A further object of the invention is to utilize a series of circular blocks adapted to receive the tool and hold the latter in various 20 angles relative to the body of the holder.

With these ends in view, this invention consists in the details of construction and combination of elements hereinafter set 25 forth and then specifically designated by the claims.

In order that those skilled in the art to which this invention appertains, may understand how to make and use the same, I 30 will describe its construction in detail, referring by numerals to the accompanying drawings forming a part of this application, in which:

Fig. 1, is a side elevation of a tool holder 35 made in accordance with my improvement.

Fig. 2, is an end view of Fig. 1.

Fig. 3, is a plan view of Fig. 1, showing the tool set at an angle to the body of the holder.

Fig. 4, is a view similar to Fig. 1 showing a modified form of tool block adapted to receive a tool but diamond shaped in cross section.

Fig. 5, is an end view of Fig. 4.

Fig. 6, is a side elevation of the body of the tool holder.

Fig. 7, is a plan view of the clamp yoke.

Fig. 8, is a side elevation of the tool holder partly in section showing another 50 modified tool block adapted to receive a tool rectangular in cross section.

Fig. 9, is an end view of Fig. 8.

Fig. 10, shows plan views of tool blocks having different width slots therein.

Fig. 11, shows end view of the block shown in Fig. 10.

Fig. 12, shows plan view of circular tool blocks having different width slots therein.

Fig. 13, is a plan view of a tool block for the reception of a tool diamond shaped in cross section.

Fig. 14, is an end view of Fig. 13.

Fig. 15, is a plan view of a circular tool block slotted to receive the tool diamond shaped in cross section.

In carrying out my invention as here embodied, 1 represents the body of the tool holder having an extension 2 formed therewith, said extension being of less width than the body of the tool holder and this extension has a dowel pin 3 set therein which projects upward therefrom. 4 represents a clamp yoke adapted to fit over the extension 2, and this yoke is provided with a set bolt 5 which passes through the lower portion thereof, and bears against the underside of the extension 2 which may be slotted for the reception for the end of this bolt so as to locate the yoke in its proper position upon the extension as will be readily understood.

6 represents a tool block which has a dowel hole 7 formed near one end of the tool block 6 which is adapted to fit over the dowel pin 3 and thus position and hold the block in place while the tool is being adjusted. The tool block 6 is grooved as indicated at 8 for the reception of a tool 9 rectangular in cross section, and this slot is intended to be of a width into which the tool may snugly fit so as to hold the latter in proper alignment with the body of the holder.

When a tool has been placed in the tool block and the yoke 4 placed around the extension and tool the setting up of the bolt 5 against the underside of the extension will draw the upper portion of the yoke upon the tool and thereby clamp the tool in the tool block and prevent any movement of the parts.

In practice it is desirable to provide a number of the tool blocks 6 each of which has a different width slot therein for the reception of different thickness in tools thus providing for the accurate guidance of said tools placed in the holder. Where it is necessary to adjust the tool at various angles to the body of the holder, I use a circular tool block 10 adapted to be seated upon the extension 2 between the side walls of the yoke 4 and having a slot 11 therein for receiving the tool 9. This will permit the tool

to be set at various angles and firmly held by the setting up of the bolt 5 one end of such adjustment of the tool being shown in Fig. 3. It is intended that a number of these 5 circular tool blocks shall be provided for each holder and that each block shall have a different width slot for the reception of tools of different thickness as it is advantageous to have the tool fit snugly within 10 the slotted block. Where a tool of diamond shaped cross-section is used the tool block 12 for the reception thereof is provided with an angular or V shaped slot as clearly shown in Figs. 5 and 14, and when this form of 15 block is used it is desirable that it shall be somewhat thicker than the other forms of blocks in order that the tool may extend backward over the body of the holder as clearly shown in Fig. 4, but it is obvious that 20 any of the blocks may be made sufficiently thick to permit the tool to extend backward over the body of the holder.

By constructing a tool holder as here shown and described relatively great strength 25 is had and a large range given to the adjustment and holding of the tools permitting the use of short as well as long tools, and by the use of the interchangeable tool blocks it is not required that the tool holder be 30 slotted as has heretofore been the practice.

Of course I do not wish to be limited to the exact details of construction as herein shown as these may be varied within the limits of the appended claims without departing from the spirit of my invention. 35

Having thus fully described my invention, what I claim as new and useful is:—

1. As a new article of manufacture, a tool holder comprising a body having an

extension of less width formed therewith, 40 a tool block supported by said extension a clamp yoke surrounding the extension, said yoke having a set bolt passing through one wall thereof for bearing against the underside of the extension. 45

2. A tool holder comprising a body, an extension formed therewith, said extension being of less width than the body, a slotted tool block fitted upon said extension, a yoke embracing the extension and tool block, a 50 tool located within said block, and a set bolt threaded through a portion of the yoke and adapted to clamp the tool carried by the tool block in position.

3. In a tool holder of the combination of 55 a body, an extension formed therewith, said extension being of less width than the body, a dowel pin secured in the extension projecting from the upper surface thereof, a tool block having a hole therein for fitting 60 over the projecting end of the dowel pin, said tool block being slotted to receive a tool, a clamp embracing said extension and tool block, a tool carried by the latter, and said bolt threaded through the lower portion 65 of the yoke and adapted to bear against the underside of the extension for clamping the parts together.

4. A tool holder consisting of a body, an integral extension projecting from the lower 70 part thereof in endwise alignment with said body, said extension adapted to support one of a number of interchangeable tool blocks, and means to hold a tool in that one of the tool blocks supported by said extension. 75

In testimony whereof, I have hereunto affixed my signature.

FRANK PRETSCH.
